UNITED STATES PATENT OFFICE.

CESARE DI CROCE, OF NEW YORK, N. Y.

CLOTHES-PRESSING BOARD.

1,277,395.

Specification of Letters Patent. Patented Sept. 3, 1918.

Application filed September 15, 1917. Serial No. 191,555.

To all whom it may concern:

Be it known that I, CESARE DI CROCE, a subject of the King of Italy, residing at New York, in the county of New York and

5 State of New York, have invented certain new and useful Improvements in Clothes-Pressing Boards, of which the following is a specification.

This invention relates to certain new and 10 useful improvements in clothes pressing boards.

The primary object of the invention is the provision of a pressing board especially adapted for use in pressing garments such 15 as trousers and skirts, the same being readily folded when not in use and automatically assuming its operative positions when released.

A further object of the device is the provision of a double board for pressing purposes whereby boards of different sizes are arranged in a single device for selective employment, one of the boards being serviceable as a base or support when the other 25 board is in use.

A still further object of the invention is the provision of a pressing board structure that is easy and inexpensive to manufacture but which possesses great strength 30 and has a smaller board arranged within a relatively larger board when the device is closed and at which times a firm support is provided for the larger board which may be used as a pressing table, a serviceable removable covering being separately arranged 35 for the boards.

With these general objects in view the device consists of the novel combination and arrangement of parts hereinafter fully described, and illustrated in the accompanying drawings and in which like designating characters refer to corresponding parts throughout the several views.

In the drawings,

45 Figure 1 is a side elevation of the device set up for use with parts broken away,

Fig. 2 is a top plan view thereof with a portion of the board cover removed,

Fig. 3 is a horizontal sectional view taken 50 centrally through the device, illustrating the smaller board in bottom plan,

Fig. 4 is an end elevation of the device,

Fig. 5 is a vertical transverse sectional view thereof taken upon line V—V of Fig. 1, 55 Fig. 6 is a side elevation of the device in

its folded arrangement with parts broken away,

Fig. 7 is an enlarged detail sectional view taken upon line VII—VII of Fig. 8,

Fig. 8 is an enlarged interior plan view 60 of a portion of the larger board,

Fig. 9 is a detailed sectional view taken upon line IX—IX of Fig. 8,

Fig. 10 is a perspective view of one of the reinforcing plates provided for the 65 smaller board,

Fig. 11 is a perspective view of one of the legs or standards for connecting the boards of the device,

Fig. 12 is a perspective view of one of the 70 hinge plates and,

Fig. 13 is an enlarged transverse sectional view of a side portion of the larger board.

It will be understood that the present device may be employed for pressing or ironing any form of fabrics although the same is especially serviceable for pressing garments or articles of wearing apparel. The invention broadly consists of relatively larger and smaller boards 10 and 11, arranged in folded relation by means of two connecting legs or standards 12 and 13, it being apparent that when either of the boards is in use for ironing purposes, the other board is employed as a base or support therefor.

The larger board 10 has a V-shaped periphery 14 and a depending flange 15, while at the ends of the board substantially semi-circular blocks 16 are arranged upon the flange 15 having depending feet 17 carried by the said blocks. Hinge plates 18 are arranged for the connecting legs 12 having the substantially triangular-shaped plate portion 19 thereof secured by screws 20 to the flange 15 and the mounting lugs 21 of the hinge plate arranged within the flange 15 within the chambered inner face 22 of the larger board 10. It will be understood that a pivot bar 33 extends through the lugs 21 of the oppositely positioned hinge plates 18 and also through perforations 34 in the abutment feet 35 of the connecting leg 12 while springs 36 encircle the bar 33 and are connected between the board 10 and the leg 12, tending to maintain the leg 12 perpendicular to the board 10.

The smaller board 11 has substantially semi-circular end blocks 16' carried by the inner face 37 thereof while two oppositely 110

positioned plates or frames 38 are carried by the face 37 between the blocks 16' and serving as overlying marginal binding strips by means of the edge portions 39 of the frame as best shown in Figs. 3 and 5 of the drawings. The leg 12 is pivoted to the smaller board 11 by means of a rod 40 passing through perforations 41 in the flanged end 42 of the leg 12 and through perforated 5 lugs 43 mounted upon the frame members 39. A spring 44 is arranged upon the rod 40, tensioned between the leg 12 and the board 11 for tending to maintain the leg 12 perpendicular to the board 11 with the 10 flange 42 seated upon the board face 37. The other leg or standard 13 is similarly pivoted to the smaller board 11 by means of a bar 40' extending through the adjacent similarly flanged end of the leg 13 and arranged with a suitable spring 44' tensioned 15 between the leg 13 and the board 11 and tending to maintain the said leg and board at right angles to each other. A suitable fabric covering 45 is arranged upon the 20 boards 10 and 11 adapted to be maintained in stretched relations thereon by means of a binding ring or hoop 46 in the form of a spring, one of the same being arranged for each of the boards. It will be seen that 25 the ring 46 for the board 10 seats itself between the block 16 and the flange 15 of the board as well as overlying the outwardly projecting hinge plate members 19 and with the fabric 45 engaged therebeneath when 30 operatively arranged. The ring 46 which is provided for the smaller board 11 is adapted for binding arrangement over the fabric 45 covering the said board and seating within the groove formed between the board 11 35 and its blocks 16' and frame-plates 39. In this manner it will be understood that the fabric covering 45 may be readily removed from either of the boards by first removing the ring 46 thereof while the same may be 40 easily arranged thereon when desired to use the board for ironing purposes.

The end of the standard 13 which is opposite the end thereof pivoted by means of the rod 40' to the board 11 is arranged with 45 abutments or feet 47 adapted to engage the inner face of the board 10 when the boards are arranged parallel in their operative positions, a connecting bar 48 being arranged between the feet 47 and having rollers 49 50 journaled upon its outer ends for readily moving upon the inner face of the board 10. A curved latch 50 is pivoted as at 51 substantially centrally of the chamber 22 within the board 10 and is arranged with 55 a head 52 having a mouth 53 for engaging over the rod 48 when the device is set up for use as best illustrated in Figs. 1 and 7 of the drawings. An operating lever 54 is pivoted as at 55 within the board 10 and 60 has its free end portion 56 arranged within

an opening 57 in the head 52, thereby normally maintaining the latch 50 in position by means of a spring 58 arranged beneath the lever 54. A finger-engaging presser-plate 59 is arranged at the outer end of the 65 lever 54 adapted for being depressed and thereby shifting the lever 54 carrying the latch 50 therewith for releasing the catch head 52 from the bar 48.

It will be understood that when the device is set up for use as shown in Fig. 1, the catch 50 will be engaged with the bar 48 for maintaining the boards 10 and 11 parallel so that either board may be seated upon a suitable support with the other 70 board elevated thereabove for use in ironing. When it is desired to fold or close the device, the plate 59 is pressed, thereby releasing the latch 50 from the standard 13 and permitting the standard 13 to be swung 75 longitudinally toward the adjacent end of the board 11 while the boards may be relatively moved toward each other obliquely, thereby causing the standards 12 and 13 to swing in opposite directions for lying 80 adjacent the board 11 with the board 11 and the standards inclosed between the block 16 and feet 17 of the board 10 as best shown by Fig. 6 of the drawings. When the boards are arranged in this manner, the smaller end 85 or heel 60 of the latch 50 will automatically engage a keeper 61 upon the inner face 57 of the board 11, thereby maintaining the device folded until the latch 50 is released 90 from the keeper 61 by pressing the plate 59. Such a releasing of the latch 50 permits the 95 spring mounting for the standards 12 to automatically separate the boards 10 and 11 bringing the notch 53 of the latch head 52 into engagement with the pivot rod 48. A serviceable double board for pressing and 100 ironing is arranged in which the larger board 10 may be positioned for use either elevated upon the smaller board 11 as shown in Fig. 1 or upon its feet 17 with the smaller 105 board folded therebetween as shown in Fig. 6. The device may be inverted for utilizing the board 11 for ironing purposes, and the board 10 for a support if found desirable. A pressing board adapted for universal use 110 is provided which is strong in construction and consumes but little room when not in use and while the form of the device herein illustrated is believed to be a preferable embodiment thereof, it should nevertheless be 115 understood that minor changes may be made therein without departing from the spirit and scope of the invention as claimed.

What I claim as new is:—

1. An ironing device comprising a large 125 board and a smaller board, spaced standards spring-hinged to the smaller board, one of said standards being spring-hinged to the other board, sliding connections arranged between the other standard and the larger 130

board, a double latch adapted for locking engagement with said sliding connections when the device is opened, a keeper carried by said smaller board adapted for engagement by the said latch when the device is folded and releasing means for the said latch adapted for operation adjacent the lower edge of the larger board.

2. A device of the class described comprising a pair of substantially parallel ironing boards, pivoted connecting means for said boards, resilient means to normally maintain said boards in parallel spaced relation, and automatic means for locking the boards in either their spaced or adjacent relations.

3. An ironing device comprising two substantially parallel boards, pivoted connecting standards between said boards, resilient means to normally maintain the boards in spaced parallel relation, and a latch for retaining the boards in their spaced or adjacent relations.

4. An ironing device comprising two substantially parallel boards, a pair of pivoted connecting standards between said boards, resilient means to normally maintain the standards parallel and the boards in parallel spaced relation, a retaining latch carried by one of the boards adapted to automatically engage one of the standards to retain the boards in spaced relation, and a keeper car-

ried by the other board adapted to be engaged by said latch to hold the boards in their adjacent relation.

5. An ironing device comprising two substantially parallel boards, a frame carried by one of said boards, a pair of standards hinged to said frame, resilient means to normally maintain the standards perpendicular to said frame with the boards in parallel spaced relation, the opposite end of one of said standards being hinged to the other board and the corresponding end of the other standard having sliding contact with said last named board, and means for engaging said sliding end of said other standard to hold the boards in their spaced relation.

6. A device of the class described comprising in combination, a pair of substantially parallel ironing boards, connecting means between said boards, resilient means to maintain said boards in parallel spaced relation, and means to retain said boards in parallel adjacent relation.

7. A device of the class described comprising a pair of substantially parallel ironing boards, resilient means to normally maintain said boards in parallel spaced relation, and means to lock said boards in their spaced relation.

In testimony whereof I affix my signature.

CESARE DI CROCE.
